UNITED STATES PATENT OFFICE.

RAYMOND N. EHRHART, OF EDGEWOOD, PENNSYLVANIA, ASSIGNOR TO THE WESTINGHOUSE MACHINE COMPANY, A CORPORATION OF PENNSYLVANIA.

CONDENSER.

1,116,042.

Specification of Letters Patent.

Patented Nov. 3, 1914.

Application filed December 31, 1912. Serial No. 739,497.

To all whom it may concern:

Be it known that I, RAYMOND N. EHRHART, a citizen of the United States, and a resident of Edgewood, in the county of Allegheny 5 and State of Pennsylvania, have made a new and useful Invention in Condensers, of which the following is a specification.

This invention relates to steam condensers and particularly to means for securing the 10 condenser shell to its support.

In connecting condensers with steam engines and particularly steam turbines it is the usual practice to provide an expansion joint between the turbine and condenser so 15 as to compensate for any expansions or distortions of either member. The usual conventional arrangement is to fasten the condenser to some rigid base, while the turbine is secured to a rigid foundation, the connection 20 between the condenser and turbine being an expansion joint. In actual practice, while the condenser is in operation, there is a lifting force on the condenser due to the difference in pressure within the condenser and 25 that without the condenser; that is to say, the atmospheric pressure has a tendency to raise the condenser shell and thereby put compression on the expansion joint. As an example, the lifting force, when under vacuum, tending 30 to raise the condenser would be the area of the exhaust times approximately 14 pounds, so that if the lifting force of the atmosphere is 75,000 pounds and the weight of the condenser is 50,000 pounds, there will be 35 a resultant lifting force of 25,000 pounds tending to tear the condenser loose from the foundation or correspondingly deflect the bed plate of the turbine when secured thereto. If the condenser shell is suspended from 40 the bed plate of the turbine, its lifting force will have a tendency to put the turbine bed plate under compression and thereby relieve the bed plate from a portion of the atmospheric pressure which it would otherwise 45 have to sustain. By suspending the condenser from the turbine bed plate not only will the upward pressure have a tendency to relieve the stresses upon the bed plate, but the condenser head may be placed closer to 50 the turbine so that the loss in vacuum during the passing of the steam from the turbine to the condenser is reduced to a minimum. By suspending the condenser from a superposed support, as for example the turbine bed

plate, the condenser shell may expand and 55 contract without rupturing the support to which it is attached.

In the drawings: Figure 1 is an elevational view of a turbine and condenser arranged in accordance with my invention; 60 and Fig. 2 is an enlarged fragmentary sectional view through a portion of the bed plate, the upper end of the condenser being shown in elevation.

Referring now to the drawings by numerals of reference: 10 designates a turbine, 11 a condenser, 12 the bed plate for the turbine, and 13 an expansion joint connecting the turbine to the condenser. The condenser is shown as being suspended from the bed plate 70 by bolts 14 passing through headed bushings 15 in the projections 16 on the condenser. There is a slight clearance between each bush and the projections 16 so as to allow for expansion in a lateral direction, while expansion in a longitudinal direction is taken care of by providing the bushings 15 slightly longer than the thickness of the flange of the projections 16. Inasmuch as the condenser is suspended above the ground it is 80 obvious that the heated condenser shell may expand, and in cooling contract without pulling away from any rigid part. It will be apparent too that when in use the difference in pressure will relieve the strain upon the 85 bed plate of the turbine to which the condenser is secured, and when not in use the weight of the condenser casting or shell will be sustained by the bed plate 12.

The pump motor 17 is shown as being fast 90 to the ground or support 18 and is connected to the pump 19 by a shaft 20 having enough flexibility to compensate for the expansion and contraction of the condenser.

Having thus described my invention, what 95 I claim is:

1. The combination of a turbine, a condenser, an expansion joint between the condenser and the turbine, and means for suspending the condenser. 100

2. The combination of a turbine, a condenser, an expansion joint between the turbine and condenser, a condenser support, and means for loosely suspending the condenser from the support. 105

3. The combination of a turbine, a support therefor, a condenser, an expansion joint between the condenser and the turbine, 110

and a support common to the turbine and the condenser from which the condenser is suspended.

4. The combination of a support, a turbine on the support, a condenser suspended from the support and in communication with the turbine.

5. In combination with an engine, a support for said engine, a steam condenser in communication with the exhaust of said engine, and means for suspending said condenser below said engine in such manner that the end is free to move vertically with relation to said support.

6. In combination with a steam turbine, a support for said turbine, a steam condenser in communication with the exhaust of said turbine, and means for suspending said condenser from said support below said turbine so that its lower end is free to move vertically. 15 20

In testimony whereof, I have hereunto subscribed my name this 28th day of December, 1912.

RAYMOND N. EHRHART.
